UNITED STATES PATENT OFFICE.

WILLIAM BURDINE BLAND, OF JENKS, OKLAHOMA.

MOWING APPARATUS.

1,228,642.

Specification of Letters Patent. Patented June 5, 1917.

Application filed June 24, 1916. Serial No. 105,734.

To all whom it may concern:

Be it known that I, WILLIAM B. BLAND, a citizen of the United States, residing at Jenks, in the county of Tulsa and State of 5 Oklahoma, have invented a new and useful Mowing Apparatus, of which the following is a specification.

This invention relates to mowing apparatus, one of its objects being to provide a 10 simple and efficient mower having means whereby the knives can be sharpened while in operation, the sharpening means being constantly under the control of the operator so as to be shifted into or out of engagement 15 with all of the knives of the mower.

A further object is to provide knives of 20 novel construction which can be sharpened readily, the cutting edges thereof being disposed out of the plane of the bodies of the knives.

Another object is to provide a finger or guard of novel construction for containing the sharpening means. A still further object is to provide mechanism of this character which can be applied easily to an ordinary finger bar.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

In the accompanying drawings the preferred form of the invention has been shown.

40 In said drawings:—

Figure 1 is a plan view of a portion of mowing apparatus embodying the present improvements, parts being broken away.

Fig. 2 is a section on line A—B Fig. 1.

45 Fig. 3 is a section on line C—D Fig. 2.

Fig. 4 is a plan view of a guard finger with the sharpening mechanism and the cover removed.

Fig. 5 is a section on line E—F Fig. 2.

50 Fig. 6 is a rear elevation of one of the knives and showing the offset cutting edges.

Fig. 7 is a plan view of the sharpener controlling mechanism connected to one end

of the finger bar, portions being broken away.

Fig. 8 is a view partly in section and partly in side elevation of the structure shown in Fig. 7.

Referring to the figures by characters of reference 1 designates a finger bar which is 60 extended over and secured to a guard plate 2 the forward end of which is preferably upcurved as at 3. Adjustably secured upon the guard plate is a clamping strip 4 having an upwardly extended ear 5 at one end and 65 a longitudinal slot 6. Bolts 7 are extended through the plate 2 and the slot 6 and also through a top plate 8 in which are formed slots 9. Spacing sleeves 10 are mounted on the bolts 7 and secured to the top plate 8 are 70 strips 11 having depending ears 12. The ears 5 on the strips 4 are designed to engage the front edge of the finger bar 1 while the ears 12 are adapted to engage the rear edge of the finger bar. The top plate 8 has slots 75 13 through which extend the bolts 14 which fasten the bar 1 to the plate 2. Thus it will be seen that the various parts can be adjusted relative to each other so that the plate 2 will be held fixed relative to the bar 1. Furthermore the parts can be adjusted to bars 80 of different widths.

Extending laterally from the rear end of the plate 2 is an extension 15 having a bracket 16 to which is pivotally connected a 85 tubular arm 17 having its upper end forked as at 18. The bolt 19 used for connecting this arm 17 to the bracket 16 can be loosened, thus to permit angular adjustment of the arm so that its upper end will be brought 90 to position close to the operator. A sheave 20 is mounted on the lower portion of the arm 17 and is engaged by a cord 21 or other flexible element preferably provided with spaced buttons or knots 22 adjacent its free 95 end. Thus the flexible element 21 can be adjusted longitudinally and held against movement in the opposite direction by seating the flexible element in the fork 18 with one of the buttons 22 against the bottom of 100 the arm.

The other end of the flexible element 21 is connected to a spring link 23 capable of expansion, this link being connected to a yoke 24 which straddles and is pivotally attached to one arm of a lever 25 journaled on

the plate 2. The other arm of this lever is connected by a link 26 to a shifting bar 27 which will be hereinafter more fully described.

Secured to the finger bar 1 at regular intervals are guard fingers 28 each of which is provided, at its rear end, with a tongue 29 extending under the bar 1 and fastened thereto by a bolt 30. A transverse rib 31 is formed on each finger at the base of the tongue and abuts against the front edge of the bar 1, each rib being extended laterally beyond each side of the guard finger 28 to form wings 32 as shown particularly in Figs. 4 and 5. A transverse ledge 33 is provided by each finger in front of the rib 31 and in front of each ledge is a longitudinal recess 34 extending close to the point of the finger and provided with an outlet opening 35 in the bottom thereof through which any moisture may drain and through which any dust or the like is free to fall.

Secured upon the finger 28 at the front end of the recess 34 is a cross strip 36 to the ends of which are attached parallel stationary blades 37 which extend along the sides of the finger and overhang the side portions of the recess 34, as shown particularly in Fig. 3. The outer edges of these blades are toothed, as indicated at 38, the teeth projecting beyond the sides of the finger 28. The rear ends of the blades 37 are attached to the projecting end portions 32 of the ribs 31 on said finger so that a longitudinal slot 39 is thus provided above the recess 34 and extending throughout the length thereof.

Arranged transversely within the bottom portion of recess 34 are pivot pins 40 and on both of these pins are mounted links 41 which are pivotally connected to ears 42 extending downwardly from the sides of a supporting plate 43. Resting on the plate is a sharpening element 44 preferably of stone, this sharpening element being held to the plate by ears 45 struck upwardly from the plate 43, or by any other suitable means. The sharpening element 44 is so proportioned as to work readily within the slot 39, it extending practically throughout the width of the slot but being slightly shorter than said slot. A spring tongue 46 which can be adjustable in length, if desired, is secured to the rear end of the plate 43, this tongue being preferably extensible by forming it with an integral loop 47. Said tongue rests on the ledge 33 and has an upstanding lug 48 which may carry a bearing sleeve or roller as shown in Fig. 1.

The lugs 48 on the tongues of the sharpening elements carried by the several fingers 28 all project into obliquely disposed slots 49 formed in the shifting bar 27 which rests upon and extends transversely of all of the ledges 33.

Extending longitudinally above the shift-

ing bar 27 is a sickle bar 50 preferably provided in its lower face with a longitudinal channel 51. Secured upon this bar are the rear ends of triangular blades or teeth 52 the cutting edges of which are offset downwardly, as at 53 so as to rest upon the blades 37, whereby the blades, in a sense, are rendered self sharpening and friction is reduced to the minimum. The sickle bar 50 is adapted to be reciprocated by any suitable means provided for that purpose.

A cap 54 is secured upon and extends longitudinally of each of the guard fingers and is spaced, at its sides, from the sides of the finger 28 so as to provide sufficient clearance to allow the blades 52 to work transversely of the guard finger. A spring member 55 is secured to the bottom face of the cap or cover 54 and carries a bracket 56 in which is journaled an anti-friction roller 57 which bears downwardly on the blades 52 adjacent thereto, thus to press the blades yieldingly onto the blades 37. Suitable oil cups 58 may be carried by the bracket 56 and an adjusting screw 59 may be employed for varying the tension of the spring member 55.

A spring bracket 60 is secured to the rear portion of the cover or cap 54 and carries an anti-friction roller 61 which constitutes a thrust bearing engaged by the rear edge of the cutter bar 50. An adjusting screw 62 may be employed for shifting the bracket 60 forwardly, thus to take up any wear which may occur. This bracket may likewise be provided with an oil cup 63 whereby the roller 61 may be lubricated.

A plate 64 may be pivoted upon the cap or cover 54 so as to extend over the adjusting screw 59 and close some oil holes 65 which may be provided in the cap or cover 54, the rear end of the plate straddling screw 62.

In operation the knives 52 will reciprocate as ordinarily, these knives coöperating with the toothed blades 37 to sever any material brought into position between the edges of the knives and the teeth 38. During this reciprocation of the knives 52, friction will be reduced by the rollers 61 and the knives will be held in their proper positions upon the blades 37 by the spring pressed rollers 57. Should it be desired to sharpen the knives 52 it will merely be necessary to pull upon the flexible element 21 so as to shift lever 25 and thrust against bar 27. This action will result in the walls of the slots 49 pulling on the lugs 48 and thus pulling through the tongues 46 upon the plates 43. This will cause the plates to move upwardly, thereby elevating the sharpening elements 44 so that they will engage the edges of the reciprocating knives 52. Spring link 23 will hold the sharpening elements yieldingly in their elevated positions. As soon as lever 25 is released it will be returned

to normal position by a spring 25' and the sharpening elements will move downward out of engagement with the knives.

It might be stated that the movement of 5 lever 25 can be limited by an adjustable stop 66 carried by the plate 2, as shown particularly in Fig. 7.

What is claimed is:—

1. In mowing apparatus, the combination 10 with a guard finger and a knife mounted to reciprocate thereacross of a sharpening element normally housed within the finger, a resilient support for said element and means for bodily lifting said sharpening element 15 against the reciprocating knife.

2. In mowing apparatus, the combination 20 with a finger bar and fingers extending therefrom, of a cutter bar mounted for reciprocation, knives secured thereto, a sharpening element mounted within each finger, and means for simultaneously shifting the sharpening elements into position for engagement by the adjacent knives during their reciprocation, said means including a 25 shifting bar, resilient members connected to the sharpening elements, and slidable connections between said members and the bar for shifting the members longitudinally during the reciprocation of the bar.

3. In mowing apparatus, the combination 30 with a finger bar and fingers extending therefrom and having recesses in their upper faces, of a holding element movably mounted within each recess, a sharpening 35 device carried by each of said elements, links pivotally connecting said holding elements to the fingers, a shifting bar slidably mounted across the fingers, means operated by the movement of said bar for simultaneously 40 pulling upon the holding elements to shift the links and move the sharpening elements out of the recesses.

4. In mowing apparatus, the combination 45 with a finger bar and fingers extending therefrom and having recesses in their upper faces, of a holding element movably mounted within each recess, a sharpening device carried by each of said elements, links pivotally connecting said holding elements 50 to the fingers, a shifting bar slidably mounted across the fingers, means operated by the movement of said bar for simultaneously pulling upon the holding elements to shift the links and move the sharpening 55 elements out of the recesses, a cutter bar, and knives secured to the cutter bar reciprocating across and between the fingers, the sharpening devices when shifted out of their normal positions engaging said knives.

5. In mowing apparatus, the combination 60 with a finger bar and fingers extending therefrom and having recesses in their upper faces, of a holding element movably mounted within each recess, a sharpening device carried by each of said elements, links pivotally 65

connecting said holding elements to the fingers, a shifting bar slidably mounted across the fingers, means operated by the movement of said bar for simultaneously pulling upon the holding elements to shift the links and move the sharpening devices out of the recesses, a cutter bar, knives secured to the cutter bar reciprocating across and between the fingers, the sharpening devices when shifted out of their normal positions engaging said knives, a cap secured upon each finger and extending over the knives and finger bar, and spring pressed means carried by the cap for bearing downwardly upon the knives.

6. In mowing apparatus, the combination 80 with a finger bar and fingers extending therefrom and having recesses in their upper faces, of a holding element movably mounted within each recess, a sharpening device carried by each of said elements, links 85 pivotally connecting said holding elements to the fingers, a shifting bar slidably mounted across the fingers, means operated by the movement of said bar for simultaneously pulling upon the holding elements to shift the links and move the sharpening devices out of the recesses, a cutter bar, knives secured to the cutter bar reciprocating across and between the fingers, the sharpening devices when shifted out of their normal positions 90 engaging said knives, and cutting elements at the sides of each finger and co-operating with the knives.

7. In mowing apparatus, the combination 100 with a finger bar and fingers extending therefrom and having recesses in their upper faces, of a holding element movably mounted within each recess, a sharpening device carried by each of said elements, links 105 pivotally connecting said holding elements to the fingers, a shifting bar slidably mounted across the fingers, means operated by the movement of said bar for simultaneously pulling upon the holding elements to shift the links and move the sharpening devices out of the recesses, a cutter bar, knives secured to the cutter bar reciprocating across and between the fingers, the sharpening devices when shifted out of their normal positions 110 engaging said knives, and cutting elements at the sides of each finger and co-operating with the knives, said sharpening devices being movable into and out of position between the blades on each finger.

8. In a mowing apparatus, the combination 115 with a finger bar and fingers extending therefrom and having recesses in their upper faces, of a holding element movably mounted within each recess, a sharpening device carried by each of said elements, links pivotally connecting said holding elements to the fingers, a shifting bar slidably mounted across the fingers, means operated by the movement of said bar for simultaneously 120 pulling upon the holding elements to shift the links and move the sharpening devices out of the recesses, a cutter bar, knives secured to the cutter bar reciprocating across and between the fingers, the sharpening devices when shifted out of their normal positions engaging said knives, and cutting elements at the sides of each finger and co-operating with the knives, said sharpening devices being movable into and out of position between the blades on each finger.

125

130

the links and move the sharpening devices out of the recesses, a cutter bar, knives secured to the cutter bar reciprocating across and between the fingers, the sharpening devices when shifted out of their normal positions engaging said knives, cutting elements at the sides of each finger and coöperating with the knives, said sharpening devices being movable into and out of position between 10 the blades on each finger, a cap secured upon each finger and extending over the knives

and cutter bar, and anti-friction means for pressing the knives in contact with the cutting elements.

In testimony that I claim the foregoing as 15 my own, I have hereto affixed my signature in the presence of two witnesses.

WILLIAM BURDINE BLAND.
